UNITED STATES PATENT OFFICE.

RICHARD J. FLOOD AND JAMES RICHARDSON, OF PITTSBURG, PA.

BUNG FOR BARRELS.

SPECIFICATION forming part of Letters Patent No. 270,942, dated January 23, 1883.

Application filed November 18, 1882. (No model.)

To all whom it may concern:

Be it known that we, RICHARD J. FLOOD, a citizen of the United States, and JAMES RICHARDSON, a citizen of Great Britain, both residing at Pittsburg, in the county of Allegheny and State of Pennsylvania, have invented a new and Improved Bung for Barrels; and we hereby declare that the following is a full, clear, and exact description thereof, reference being had to the accompanying drawings, forming part of this specification, wherein—

Figure 1 represents a solid metallic and right-handed screw-plug, having a large flat circular head, provided at equidistant points around its rim with three radial notches; Fig. 2, a top view of the plug-head. Fig. 3 represents a side elevation of a metallic tube provided with a left-handed exterior screw and a flat circular head, also furnished with three radial notches in the edge of its rim; Fig. 4, a top view of the head of the tube; Fig. 5, an external view of our improved separable bung, consisting of the solid metallic plug fitted and screwed into the hollow of the stout metallic tube; Fig. 6, a transverse vertical section of the same. Figs. 7 and 8 simply show the notched and disk-like top or head of the solid plug, and are mere repetitions of the view Fig. 2.

Our invention consists of a separable metallic bung formed in two parts, one of which is a short stout tube, *a*, provided exteriorly with a left-handed screw, *b*, and at one end with a flat circular projecting flange, *c*, having in its edge, at equidistant points, three radial square notches, *d d d*, by which said tube may be caught and tightly screwed into a barrel. The interior of this tube *a* is formed with a right-hand screw, *f*, and into this a solid metallic plug, *e*, provided with a correspondingly-shaped screw, *g*, is made to fit. This plug is also provided with a circular flange or flat pro-

jecting head, *h*, in the edge of which are cut or otherwise formed three radial notches, *i i i*, answering in shape and size to those in the flange of the tube *a*, just described. This tubular portion *a* of the bung is intended to be screwed permanently in a stave or head of a barrel, and used in connection with the solid plug *e*, in such a manner as that the tube may be securely closed when the barrel is full, or slightly opened by a partial turn of the plug to admit air in such quantities as will allow the contents of the barrel to be drawn off through a spigot, if desired; or the projecting flange of the plug may be so snugly screwed down upon that of the tube as to practically make the joint existing between them air and water tight; or the plug may be readily unscrewed and removed from the tube through which the barrel may be filled, or for other purposes.

Having described our improved metallic bung, we claim—

A separable metallic bung formed in two parts, one of which consists of a short stout tube, *a*, provided interiorly with a right-hand screw, *f*, and exteriorly with a left-hand screw, *b*, and at one end with a flat circular projecting flange, *c*, having in its edge, at equidistant points, three radial square notches, in combination with a solid metallic plug, *e*, provided with an external screw, *g*, corresponding to that in the tube *a*, and with a flat circular projecting flange, *h*, having in its edge three radial square notches, arranged at equidistant points, as shown and set forth.

RICHARD J. FLOOD.
JAMES RICHARDSON.
